EGG CANDLING DEVICE

Joseph J. Baiocchi, San Francisco, Calif.

Application May 30, 1944, Serial No. 538,043

1 Claim. (Cl. 88—14.92)

This invention relates to improvements in egg candling devices.

It is in general the broad object of the present invention to provide a new, improved egg candling device in which maximum utilization of light derived from a light source is secured.

Another object of the present invention is to provide an egg candling device including a reflector in combination with means for ventilating the casing of the device so that moisture, dust and other foreign matter does not collect upon nor mar the surface of the reflector.

A further object of the present invention is to provide a simple and inexpensive egg candling structure which is readily manufactured of standard parts, has a low operating cost, and can be easily maintained.

The invention includes other objects and features of advantage some of which, together with the foregoing, will appear hereinafter wherein the present preferred form of device is disclosed.

In the drawing accompanying and forming a part hereof, Figure 1 is a side elevation, partly in section, taken along the line 1—1 in Figure 2. Figure 2 is a view taken along the line 2—2 in Figure 1.

Figure 3 is a front view of the device shown in Figure 1.

The device of the present invention includes an outer casing 3, generally made of sheet metal, in the form of a rectangle and having sides 4, 5, 6 and 7, a top 8, and an open bottom defined by a flange 9. An auxiliary cover or casing 11 is mounted upon side 4, to which it is secured by screws 12. An incandescent lamp socket generally indicated at 14 is mounted upon top 8 of the casing. The socket is formed of two portions, an upper portion 15 and a lower portion 16, the two being separable to permit the socket to be installed, portion 16 being thereafter secured in place to retain the socket rotatably upon the top 8.

An incandescent lamp generally indicated at 17 is secured in the socket, the lamp having a screw type base 18 from which a central support 19 extends together with support wires 21. A filament 22 is extended between the wires in a substantially straight line at right angles to the longitudinal axis of the lamp to provide a source of light.

A lens 23 is mounted over an aperture 24 in side wall 4 and is retained in place by a rim 26 formed on the side wall. The lens is positioned at right angles to the extended longitudinal axis of the straight line filament 22 when the lamp is posi-

tioned as shown in Figure 1. Cover 11 includes an aperture therein to permit emission of light passing through the lens from the light source, this aperture being covered by a rubber ring 21, retained in place about the aperture in the cover by its own resilience and its fit in the aperture.

To ensure maximum light emission, a reflector 31 is provided on a movable mounting generally extending through a threaded ball 34 which is indicated at 32 and including a threaded rod 33 rotatably mounted in an aperture in wall 5. The screw mounting enables the reflector to be advanced toward and away from the light source, a lock nut 35 enabling the reflector to be secured 15 in a desired adjustment. To secure the reflector in the desired rotated position, a lock device generally indicated at 38 is provided. This includes a ring 39 surrounding the ball 34, a screw 41 and a wing nut 42, the screw being secured to the 20 casing so that when the wing nut is tightened the ring 39 rocks about its extension 43 which bears against the casing thus forcing the ring 39 to engage and hold the ball firmly in an adjusted position.

25   The position of the reflector with respect to the light source can be varied. Because incandescent lamps are not uniform, the distance between the filament 22 and the base varying, I provide means enabling the position of the reflector to be adjusted to secure maximum light emission. In Figure 1, I have shown the reflector as positioned slightly below the filament 22 and below the central point of the lens. The three 30   can be placed in alignment, that is, the central point of the lens, the filament, and the axis of the reflector can be placed on a line, if desired. However, the construction shown is satisfactory and permits ready adjustment because the reflector can be rocked about its support to accommodate the various lamps found commercially.

In operation, a lamp is inserted into the socket and is turned so that its filament is at right angles to the inside face of lens 23. Then the reflector is moved toward or away from the filament and is rocked into that position giving the maximum light emission, this being suitably measured as on a photometer or light meter. In practice, the device is suitably supported in the position in which it appears in Figure 1. By placing a translucent sheet of glass at 46 and supporting this on flanges 9, a sufficient light transmission can be secured so that an operator has sufficient light to pick up the eggs to be candled.

55 The casing 3 includes louvers 41 along each

lower edge of sides 6 and 7 and an exit louver 48 in top 8 to permit air to circulate freely through the casing so that moisture and dirt do not collect on the reflector, being carried out by the air passing through the casing due to the heat of the lamp. An aperture 49 is also provided in wall 4 between the casing and cover 11 to permit air circulation.

In candling white eggs, the natural light from the lamp suffices. In candling brown eggs, light of another color enables the operator to judge the egg more accurately. To facilitate this, a suitable filtering device indicated generally at 51 is mounted on screw 52. This device includes a suitable green colored filter which can be selectively moved into position over the aperture by rod 53.

From the foregoing I believe it will be apparent that I have provided a new, novel, simple and efficient egg candling device which can be readily adjusted to permit of ready candling of eggs with maximum light utilization.

I claim:

An egg candling device comprising a casing having a top, sides and bottom, louvers in the sides and top of said casing to permit air circulation through said casing, a lamp, means supporting said lamp from the top of the casing, said

casing also including a light emission aperture in a side thereof, a lens mounted in said aperture, said lamp including a filament extending in a straight line between two supports in the lamp, 5 said lamp being mounted in a position wherein the filament coincides with a line passing at right angles through the center of the lens, a reflector positioned adjacent the lamp and on that side of the casing which is opposite said lens, means 10 supporting the reflector for movement toward and away from the filament, said means including ball and socket means supporting the reflector for rotation about the lamp, an auxiliary casing mounted exteriorly of said casing on one side 15 thereof and having an aperture therein to permit a beam of light from said lens to pass therethrough a ring of resilient material fitted in said aperture for receiving an egg to be candled, a light filter, means mounting said filter within 20 said auxiliary casing for movement between a first position in which said filter is interposed in the path of said beam between said auxiliary casing aperture and said lens and a second position in which said filter is disposed out of said light beam but within said auxiliary casing, and means 25 extending through said auxiliary casing for moving said filter between said positions.

JOSEPH J. BAIOCCHI.
